UNITED STATES PATENT OFFICE

SAMUEL SHEPPARD AND OTTO BANKER, OF MANKATO, MINNESOTA

CULTIVATOR

Application filed October 8, 1931. Serial No. 567,702.

This invention relates to a cultivator adapted more especially for use in cultivating small areas.

One of the objects is to provide a wheel 5 cultivator which has a handle so shaped as to allow the user to walk in the rear thereof and thrust thereagainst without trampling upon the row being cultivated.

Another object is to simplify and otherwise 10 improve upon devices of this character.

With the foregoing and other objects in view which will appear as the description 15 proceeds, the invention resides in the combination and arrangement of parts and in the details of construction herein described and claimed, it being understood that changes in the precise embodiment of the invention herein disclosed may be made within the scope 20 of what is claimed without departing from the spirit of the invention.

In the accompanying drawings the preferred form of the invention has been shown.

In said drawings:

Figure 1 is a plan view, the handle being 25 broken away.

Figure 2 is a section on line 2—2, Figure 1.

Referring to the figures by characters of reference, 1 designates an axle supported by 30 wheels 2 and provided at its center with a small integral yoke 3. The forked upper ends 4 of standards 5 are arranged astride and are clamped to the axle near the respective sides of the yoke and journaled on the lower end of each standard is a disk plow 6 35 set at the proper angle to hill a row.

Additional spring standards 7 are clamped to the axle between the wheels and the disk plows and carry blades 8 for cultivating between rows.

The yoke 3 is extended upwardly between opposed stiff metal strips 9 which are parallel and can have offset free ends 10 forlapping the front edges of the sides of the yoke so that when the strips 9 are clamped to the yoke by transverse bolts 11 they will be held 40 against movement relative thereto.

Intermediate portions of the strips 9 are offset obliquely as at 12, and then merge into rearwardly extending parallel portions 13 which extend along opposite sides of an elongated handle 14 to which they are fastened by bolts 16. A spacing block 15 is secured between the oblique portions 12 to lend rigidity to the structure.

It will be noted that by mounting the 55 handle as described it will be located at one side of but parallel with the center line of the cultivator. Thus, when the operator takes his position back of the handle and thrusts thereagainst, he can walk forwardly 60 without treading on the row being cultivated. The connection between the handle and axle is simple and efficient and allows for easy assembly and disconnection of the parts.

What is claimed is:

1. A cultivator including a wheel supported axle having a yoke, rigid strips clamped at one end to opposite sides of the yoke, a handle secured to the other end of the strips, intermediate portions of the strips being offset laterally along diagonal lines, and a spacer secured between the offset portions. 65

2. A cultivator including a wheel supported axle having an integral yoke, a handle, parallel strips secured at one end to one end portion of the handle, the other ends of the strips being extended to opposite sides of and engaging the yoke, means for fastening the strips to the yoke, means on the strips cooperating with the yoke for holding them 70 against relative rotation, the intermediate portions of the strips being offset laterally along oblique lines, and a filler secured between said oblique portions. 75

In testimony that we claim the foregoing 80 as our own, we have hereto affixed our signatures.

SAMUEL SHEPPARD.
OTTO BANKER.
